United States Patent Office

Des. 222,581
Patented Nov. 9, 1971

222,581

DISPLAY PACKAGE FOR BATTERIES OR THE LIKE

Keiichi Nakakuma, Tokyo, Japan, assignor to Fuji Denki
Kagaku Kabushiki Kaisha, Tokyo, Japan

Filed June 30, 1970, Ser. No. 23,762

Term of patent 14 years

Int. Cl. D9—03

U.S. Cl. D9—183

FIG. 1

FIG. 2

FIG. 3

FIG. 4

FIG. 5

FIG. 6

FIG. 1 is a front perspective view of a display package for batteries or the like showing my new design;

FIG. 2 is a side elevation view thereof;

FIG. 3 is a top plan view thereof;

FIG. 4 is a perspective view thereof in open condition showing the front and rear;

FIG. 5 is a side elevation view of FIG. 4; and

FIG. 6 is a top plan view of FIG. 4.

I claim:

The ornamental design for a display package for batteries or the like, as shown and described.
